BOW SAW

Hermann Burkhardt, Weiningen, Switzerland

Application May 31, 1934, Serial No. 728,391
In Switzerland June 10, 1933

1 Claim. (Cl. 145—32)

The present invention relates to improvements in buck hand saws and the object of my invention is to provide a saw more simple and of cheaper design than those in use up to now and also one which can be handled easier in places difficult of access and which easily can be taken apart and put together. To attain these objects the new saw consists of two straight wooden uprights of the same shape, a metal bow with ends bent down at an angle loosely abutting against and engaging into recesses of the uprights in the manner of knuckle-joints, tension-rods actuated by wing-screws attached at one end to the angular points of the metal bow by means of articulated joints and lying at the other end in the prolongation of the mean part of the bow in slits of the uprights open on top, a blade carried parallel to the mean part of the bow, said bow, tension rods and blade forming the only transversal parts between the uprights.

The accompanying drawing exemplifies an adaption of the invention and shows:

Fig. 1—a lateral view of the saw, partly in section;

Fig. 2—the detached bow;

Fig. 3—the blade with the uprights in another position; and

Fig. 4—a section along line I—I of Fig. 2.

Blade 1 at its ends is provided with adjusting pins 2 connected by means of articulated joints, said pins passing through bores of the uprights 3, the latter consisting of straight wooden pieces and the blade possessing handles 4 bearing on the uprights. 5 is a metal bow, having in the design shown an intermediate straight part 6 with ends 7 bent down at a sharp angle. Ends

8 of said ends 7 rest loosely, with some play, in recesses 9 of the uprights 3.

Tension-rods 11, carrying wing-screws 13, pass through slits 12 open on top, of uprights 3, said tension-rods acting on straight part 6 of bow 5 by means of forks 10 jointed loosely to said bow. When tightening or slackening the blade, by turning the wing-screws 13, ends 8 form fulcrums for the uprights 3 on bow 5.

My saw has the following advantages: there are but two horizontal transverse parts, that is blade 1 and the mean part of bow 5 parallel to it, so that between the two there is provided much room to work in; since the ends of bow 5 are bent down at an angle, wing-screws 11 are aligned with the mean part of bow 5 (see Fig. 1), giving rise to favorable tensile stresses; since ends 8 rest loosely in uprights 3, and the wing-screws 11 sit in slits 12 open on top, the saw can easily be taken apart and put together. The straight wooden pieces of the uprights 3 can easily and cheaply be made.

I claim:

A buck hand saw having two straight wooden uprights of the same shape, a metal bow with ends bent down at an angle loosely engaging in recesses of said uprights, tension-rods with wing-screws at one end attached to the angle-points of the bow by means of a joint and at the other end lying in alignment with the mean part of the bow in slits of the uprights open on top, a blade parallel to the mean part of the bow, said blade, bow and rods forming the only transversal parts between the uprights.
